UNITED STATES PATENT OFFICE.

JAMES N. CROCKER, OF SARATOGA SPRINGS, NEW YORK.

TIME DAMPER MECHANISM.

SPECIFICATION forming part of Letters Patent No. 726,873, dated May 5, 1903.

Application filed May 11, 1901. Serial No. 59,718. (No model.)

To all whom it may concern:

Be it known that I, JAMES N. CROCKER, a citizen of the United States of America, and a resident of Saratoga Springs, Saratoga county, 5 and State of New York, have invented certain new and useful Improvements in Devices for Automatically Opening and Closing the Drafts of a Furnace, of which the following is a specification.

10 My invention relates to time damper mechanism; and the object of my invention is to provide an automatic device operated by clockwork for opening and closing the drafts of a furnace at a predetermined time. I at-
15 tain this object by means of the mechanism illustrated in the accompanying drawings, in which—
Figure 1 is an elevation with parts broken away. Fig. 2 is a longitudinal section. Fig.
20 3 is a detail view showing the means for making and breaking contact between the spring-lever S and the wheel W. Fig. 4 is a detail view of the clock-face. Fig. 5 is a detail view with parts removed, showing the connection
25 of the spring-lever S, wheel C, and hand D, and means of operation by the wheel W when connected with the offset s on spring-lever S. Fig. 6 is a plan of the spring-lever S. Fig. 7 is a side elevation of spring-lever S. Fig. 8
30 is a detail perspective view of the cam-shaped hub E.

Similar letters refer to similar parts throughout the several views.

I arrange a clock A, having a gear-wheel B, 35 adapted to engage with a gear-wheel C, the wheels B and C having an equal number of teeth. The gear-wheel C is mounted upon the shaft c, which also carries the hand D. Upon the wheel C, I arrange a cam-shaped 40 hub E, said cam being inclined and having a cut-away portion, as at c². Upon the shaft C is a pin F, with which the cam-hub E engages, for a purpose to be presently explained. To the rear of the face A, I secure one end of the
45 spring-lever S in any suitable manner, said spring-lever S provided with an opening 10, by means of which it is placed loosely on the shaft C, and provided at its end opposite that to which it is fastened to the clock-face, with
50 preferably a projecting offset s, adapted to engage with the pin T on the wheel W. The gear w of the wheel W meshes with the gear

on the wheel V, and the pinion v engages with the gear on the wheel X. To the wheel X is arranged a dog L and ratchet Y. I also ar- 55 range a drum Z on the shaft x, carrying the wheel X, about which I coil a rope R. The shaft x is squared at M, preferably, to fit a key by means of which the rope may be wound on the drum, the wheels being held from re- 60 volving during the winding by the spring-lever S engaging with the pin T on the wheel W. The rope R is wound about shives N and is attached to suitable lever O, engaging with the dampers P P' of the furnace F. 65

In setting the apparatus the supplemental hand D is moved to the hour on its dial at which it is desired the dampers shall be operated. This movement of the hand D causes the shaft C to be turned and the pin F on the 70 shaft c to ride up the inclined cam-hub E, thus moving the wheel C on its shaft and bringing the offset s on spring S into engagement with pin T on wheel W, thus locking the train of gearing and permitting the shaft 75 x to be turned, winding the rope R about the drum Z, opening damper P and closing damper P'. The apparatus being set, as the hour-hand of the clock moves the wheel B on its shaft will turn, and being in gear with the 80 wheel C will cause said wheel to turn, which will bring the cut-away portion of the cam on its hub in such position to permit the wheel C to be moved by the spring S, this movement of the spring freeing its offset from the pin T 85 on the wheel W, thus unlocking the train of gearing, whereupon the weighted lever O will fall, closing damper P and opening damper P'.
90

What I claim as my invention, and desire to secure by Letters Patent, is—
In a damper-operating device the combination with a clock, a train of gears, the drum carried by one of the wheels of said train, the rope or flexible connection carried by said drum and connected meditately with the dampers of a furnace, a supplemental setting-hand, the shaft c upon which it is mounted, the wheel movable longitudinally on said shaft, a wheel on the clock-hand shaft, in gear with the wheel-shaft c, the inclined cam-hub on the supplemental hand-wheel C having cut-away portion, the pin on the shaft c adapted to engage with said inclined cam, the spring-lever attached to the rear of the 95 100

face of the clock and pressing against the wheel on the shaft *c* to move said wheel on the shaft, the offset on one end of said spring, the pin on one of the wheels of the train of 5 gears, with which the offset engages to lock the train, until the inclined cam is brought to such position to bring its cut-away portion in line with the pin on the shaft *c* by the movement of the hour-hand of the clock, 10 when the spring-lever will assert itself, moving the wheel *c* on its shaft and free the offset

on the spring-lever from the pin on the wheel of the gear-train, permitting the lever *O* to drop and close and open the dampers of the furnace.

15

Signed at Albany, New York, this 8th day of May, 1901.

JAMES N. CROCKER.
